UNITED STATES PATENT OFFICE.

EDWARD KIRBY BOTTLE, OF NEW YORK, N. Y., ASSIGNOR TO THE CARTER-CRUME COMPANY, LIMITED, OF NIAGARA FALLS, NEW YORK, A CORPORATION OF CANADA.

TRIPPLICATE MANIFOLDING SALES-BOOK.

No 846,002.

Specification of Letters Patent.

Patented March 5, 1907.

Application filed April 14, 1904. Serial No. 203,153.

To all whom it may concern:

Be it known that I, EDWARD KIRBY BOTTLE, residing at New York, in the county of New York and State of New York, have invented certain new and useful Improvements in Triplicate Manifolding Sales-Books, of which the following is a full, clear, and exact description, such as will enable others skilled in the art to which it appertains to make and use the same.

This invention relates to sales-books. One of the objects thereof is the production of a durable, efficient, and inexpensive triplicate book.

Another object is to provide a book of the above type which may be readily used either with or without an auxiliary outer cover.

Other objects and advantages will be in part obvious and in part pointed out herein-after.

The invention accordingly consists in the features of construction, combinations of elements, and arrangement of parts, which will be hereinafter fully described and the scope of the application thereof pointed out in the claims.

In the accompanying drawings, which show one embodiment of my invention, of which various embodiments will readily occur to those skilled in the art, Figure 1 is a perspective view thereof, showing the parts opened in order to disclose the construction more clearly. Fig. 2 is a similar view of the device in condition for use.

Similar reference characters refer to similar parts throughout both views of the drawing.

The part 1 represents a pad the leaves of which are preferably made of tissue-paper or other similar material and secured to rigid back 2. By the word "rigid" throughout this specification and the following claims is meant the stiffness or non-flexibility of some material possessing these properties to about the same degree, so far as results are concerned, as heavy cardboard. The back 2 projects at one end beyond the pad 1 and is secured at that point by stapling or other desired means to a flexible strip 3. This strip is preferably made of heavy manila paper, and by the word "flexible" as used throughout this specification and the following claims is meant the pliability of a substance possessing this property in about the same degree, so far

as results are concerned, as the above-mentioned paper. The strip 3 terminates at a point below the upper or stub end of pad 1 and is connected to the upper end of a second pad 4. The latter pad terminates at its upper end at a point directly over the upper end of strip 3 and at its lower end at a point directly opposite the lower end of pad 1 and is preferably coextensive in width with both pad 1 and strip 3. Such arrangement and relation of parts as to size and connection has been found most convenient in practice, but could obviously be varied, if desired, without departing from the principles of the invention.

Pad 4 comprises a plurality of folded leaves secured at the upper end at stub 4^a by stapling or other desired means. Each leaf comprises a portion 5, extending downwardly from the stub 4^a, and is folded at the lower end so as to form a shorter upwardly-extending portion 6. At the junction of parts 5 and 6 and the junction of part 5 with the stub 4^a the leaf is preferably perforated or otherwise weakened, so that it may more readily be torn at those points. There is also secured to the stub 4^a in front of the several above-mentioned leaves a double-transfer sheet 7, made of carbon or other transfer-paper. The transfer-sheet substantially corresponds in shape with the leaves of pad 4 in their folded position and is adapted to lie smoothly between the parts 5 and 6 of the same.

The upwardly-projecting end of pad 1 and the accompanying extremity of back 2 may, if desired, be detachably secured within an outer or auxiliary covering 9 by means of a spring-clip 10 or other fastening means. The preferred form of covering 9 is composed of two rigid members, adapted to extend over the entire front and rear surfaces of the associated pads, and a flexible portion connecting the rigid members at the upper ends. The entire covering is preferably bound in leather or other suitable material, so as to render the same more durable. Pockets 11 and 12 may be formed, if desired, at each end of the upper member of the auxiliary cover for the purpose of retaining a card, upon which further record may be kept.

Other retaining means may be used in place of spring-clip 10, and there is preferably attached to the rear of back 2 a tongue

12^a of manila paper or other suitable material. This tongue protects the back from the clip 10 and is useful in connection with certain other types of retaining means if the same are used in place of clip 10.

The operation of the embodiment herein set forth is as follows: The book is held in the left hand, and the outer covering, if used, is raised, whereupon the pad 4 is swung away from pad 1, as shown in Fig. 1 of the drawings, and one of the thin leaves of the latter pad is raised. The outer portion 6 of the upper folded leaf of pad 4 is then raised to permit the transfer-sheet to fall against the portion 5. Pad 4 is then folded against the remainder of pad 1 and the raised leaf of the latter inserted between the portion 6 and the transfer-sheet, this portion being then folded back to place the book in the condition shown in Fig. 2. The above operation may be easily performed with one hand, leaving the other hand free to hold the book. With the book in the condition above described the writing is done upon the exposed surface 25 of the portion 6 of the upper leaf of pad 4, and the pressure of the pencil or other writing means is transmitted through the interposed leaf of pad 1 to the double-transfer sheet 7, as will be obvious from the relative 30 position of the leaves, as shown in Fig. 1 of the drawings. The transfer-sheet 7 transmits the writing to portion 5 of the upper leaf of pad 4 and also upwardly to the interposed leaf of pad 1, and on account of the thin material of which the latter leaf is formed it may be easily read through the same from the upper surface thereof. There are thus formed, aside from the original upon the part 6, two duplicate copies of the same—namely, that upon the leaf of pad 1 and that upon the portion 5 of the leaf of pad 4. The original upon part 6 and the duplicate upon part 5 may now be detached and separated and one given to the bookkeeper and the other to the customer, or such other disposition made of them as is desired. The duplicate copy upon pad 1 is in the customary use of the book retained in the same by the salesman; but it is obvious that that copy 45 could also be detached, if desired.

Although the device may be used as above set forth, a method of use which is in general considered preferable is as follows: The pad in its closed normal condition is arranged with the unused portion of pad 1 resting smoothly upon, instead of under, the pad 4, as above described. When it is desired to make an entry, the superimposed portion of pad 1 is folded back away from pad 4 and the outer portion 6 of the upper leaf of the latter pad is raised to permit transfer-sheet 7 to fall upon the portion 5 thereof and the lowermost leaf of pad 1 is laid upon the transfer-sheet. Upon portion 6 being then folded upon the selected sheet of pad 1 the

entry is made as above described and the book restored to normal condition by merely swinging pad 4 about its connection with back 2, thus allowing the used leaf of pad 1 to fall beneath the rigid back of the pad. It will be noted that this method of use differs from that first described chiefly in that the pad 1 is used from the back toward the front thereof, thus rendering its manipulation more rapid and simple.

The advantages of the construction herein set forth should be in great part obvious. The simple and yet efficient manner of connection, such that the essential parts are secured together and not separated in practice, is of importance, as in former types of triplicate sales-books much confusion and annoyance has been caused by the separation of the several parts or by clumsy and inefficient connection thereof. Advantages which should be especially noted as distinguishing the present invention reside in the durability of the connections between the various elements and the ease with which the book may be used without an auxiliary cover. The flexibility which it is possible to allow to strip 3, due to the fact that it is separate from the back 2, and is thus not depended upon to perform the functions of a back, renders the breaking of this strip at the lower end impossible in the course of any ordinary use. In preceding books of this type it has been necessary to make use of an auxiliary outer cover to efficiently use the book. This has been due to the fact that it has been attempted to carry the flexible connection between the upper and lower pads to the rear of the lower pad, so as to form a back for the same. The attempt to make this back sufficiently rigid has resulted in the breaking of the same at the point at which bending is required. The above and other defects are remedied in the construction herein set forth. Although my device is eminently suited for use in connection with an auxiliary cover and the embodiment shown in the drawings discloses such a cover in connection therewith, yet the necessity for such an outer covering is obviated, and the pad may be conveniently and efficiently used without the same.

The embodiment herein described is obviously only one of many possible embodiments of my invention, and for that reason I intend that the statements herein made and the construction shown in the accompanying drawings shall be construed as merely illustrative thereof and not as limiting the same.

Having described my invention, what I claim as new, and desire to secure by Letters Patent, is—

1. In a device of the class described, in combination, a rigid back, a pad positioned thereon and secured thereto at one end thereof, a second pad comprising a plurality of leaves, each of which is folded upon itself,

5 a flexible connection between the lower end of said back and the upper end of said second pad, said connection passing between said pads and a double-faced transfer-sheet secured to said second pad.

2. In a device of the class described, in combination, a rigid back, a pad positioned thereon, a second pad comprising a plurality of leaves each of which is folded upon itself, a flexible connection secured flat against the lower end of said back and extending between the said pads to the upper end of said second-mentioned pad and a double-faced transfer-sheet secured to said second-mentioned pad.

10 3. In a device of the class described, in combination, a pad, a rigid back upon which said pad is positioned said back projecting

15 below said pad and being secured thereto at the upper end thereof, a second pad comprising a plurality of leaves each of which is folded upon itself, a flexible connection secured flat against the projecting lower end of said back and passing between said pads and secured to the upper end of said second-mentioned pad, and a double-faced transfer-sheet secured to said second-mentioned pad, said first-mentioned pad in normal position projecting above the end of said second-mentioned pad.

20 25 30 In testimony whereof I affix my signature in the presence of two witnesses.

EDWARD KIRBY BOTTLE.
